BOWLING ALLEY

Henry E. Gremp and Edward C. Gremp,
Chicago, Ill.

Application May 13, 1939, Serial No. 273,381

9 Claims. (Cl. 273—51)

Our invention relates in general to runway construction, and has more particular reference to bowling alleys.

An important object of the invention resides in providing a runway construction well adapted for use as a bowling alley, the runway being inexpensive, yet durable, and made of parts sized to facilitate and minimize the cost of transportation, said parts being formed for easy assembly in building the alley thereby reducing the cost of providing bowling alleys at the location where set up for use.

Another important object is to provide an alley construction comprising sectionalized parts prefabricated for ready assembly in the construction of bowling alleys; a further object being to utilize sheet metal sections for the construction of the alley.

Another important object is to provide an alley construction having simplified means for leveling the floor thereof, thereby insuring true rolling characteristics in the floor.

Another important object is to provide a bowling alley having a composition floor supported on a suitable basic floor structure whereby the alley may be erected in position exposed to the outdoor elements without impairing the same throughout a long service life.

Another important object is to provide a bowling alley of prefabricated metal parts; a further object being to make the pit end structure of the alley of sheet metal parts and to provide sound absorbing means thereon to suppress the noise of ball impact.

Another important object is to provide an outdoor bowling alley which need not be enclosed or protected from the weather.

Another important object is to utilize sheet metal sections to form gutters in the bowling alley structure.

Another important object is to form a bowling alley gutter with a depressed trough in the bottom thereof carrying tracks for balls therein; a further object being to form the gutter on each side of the depressed trough with curved walls in order to urge a ball toward and onto the tracks.

Another important object is to interconnect the adjacent gutters of adjacent alleys by means of a closure formed to provide a ball return track between adjacent alleys; a further object being to form said closure as a sheet metal piece carrying ball tracks adapted to convey balls returned from the pin or pit end of the bowling alley to the delivery end thereof, said return track also

serving to receive and catch such wildly thrown balls as may pass from one alley over the lateral gutter thereof and thereby prevent such balls from passing onto the adjacent alley.

5 Another important object is to provide a ball return way of sheet metal extending from the pit to the approach end of the alley; a further object being to utilize the return way as a cover or finishing piece for interconnecting and enclosing the space between adjacent alleys; and a further object is to provide a ball rack at the approach end of the alley comprising an extension of the return way; a still further object being to provide an improved ball check on said rack.

10 Another important object is to provide a bowling alley including a sub-structure supporting the alley floor and bracket means at intervals extending from said sub-structure laterally of said floor and beneath the lateral gutters whereby to support the same; a further object being to provide sheet metal brackets of simplified construction extending at spaced-apart intervals between the sub-structures of adjacent alley constructions and affording support for the adjacent gutters of adjacent alleys, and also support for the closure member which forms a ball return between said adjacent alleys, said ball return being readily removable from mounted position between such adjacent gutters in order to afford a space therebetween through which the alley leveling means may be manipulated, as by the insertion of the arm of a service operator through the opening between adjacent gutters.

15 Another important object is to utilize tubular sheet metal sections to form ball tracks on the gutters and in the ball return way; a further object being to anchor the track elements in place by means of snap fasteners comprising spring arms on and projecting from the track elements in position to snap into and lock in openings formed in the gutter and return way elements, said snap fasteners comprising detents which may be released from locking position merely by squeezing the same together on the side of the gutter and return way members opposite from the side thereof on which the track elements are mounted.

20 Another important object resides in providing countersunk and sealed, yet readily operable, fastening means for interconnecting adjacent gutter sections whereby the fastening means is depressed below or behind the attached gutters so that the balls may not become nicked thereby, the fastening means, however, being readily operable from above in order to either connect or

disconnect the gutter sections, thereby facilitating alley assembly operations.

Another important object resides in providing a sub-floor structure, more particularly for bowling alleys, comprising sectionalized metal structural elements and means to support the same adjustably in position to carry the alley floor; a further object being to provide simplified means for adjusting the elevation at which each section is mounted; a still further object being to dispose the adjusting means below the alley floor in position readily accessible from above the alley construction.

Among the other numerous important objects of the invention are to provide an inexpensive bowling alley construction in which substantially all of the parts of the structure, including the floor supports, the gutters, and the ball return way, comprise metallic parts of inexpensive form and preferably made up in standard lengths so that the structure may be shipped in completely knocked-down condition, thereby minimizing transportation costs; a structure of which all of the parts comprise relatively simple metallic sections adapted for inexpensive prefabrication, as at a factory, for shipment to the eventual alley erection site and there erected merely by fastening the parts together; a structure affording facilities for accurately leveling the alley floor after the same has been erected in place, in order to true up the floor for bowling; a construction in which none of the parts are subject to deterioration whereby the alley may be erected for outdoor operation; a structure which requires no foundation other than spaced-apart blocks on which to rest the structure; and in general, a structure that may be erected anywhere at minimum expense to afford a bowling alley having superior characteristics insofar as the travel of balls thereon is concerned, as well as the ability to resist deterioration upon exposure to the outdoor elements.

These and numerous other important objects, advantages, and inherent functions of the invention will become apparent as the same is more fully understood from the following description, which, taken in connection with the accompanying drawings, discloses a preferred embodiment of the invention.

Referring to the drawings,

Figure 1 is a perspective view of a bowling alley embodying our present invention;

Figures 2, 3, 4, and 6 are enlarged sectional views taken substantially along the lines 2-2, 3-3, 4-4, and 6-6 in Figure 1;

Figure 5 is a sectional view illustrating a modified form of a part of the device as illustrated in Figures 4 and 6;

Figure 7 is an enlarged sectional view of a portion of the structure shown in Figures 4 and 6;

Figure 8 is a perspective view of a snap fastener used in the construction shown in Figure 7;

Figure 9 is a sectional view taken substantially along the line 9-9 in Figure 6;

Figure 10 is a sectional view taken substantially along the line 10-10 in Figure 4;

Figures 11, 12, and 13 are enlarged sectional views taken substantially along the lines 11-11, 12-12, and 13-13 respectively in Figure 2;

Figures 14, 15, and 16 are sectional views taken substantially along the lines 14-14 and 15-15 in Figure 11, and 16-16 in Figure 15; and

Figure 17 is a sectional view taken substantially along the line 17-17 in Figure 1.

To illustrate our invention we have shown on

the drawings a bowling alley structure 11 comprising means forming a pair of adjacently disposed alleys 13 forming a bowling alley set, each alley comprising a runway or floor 15 having a pit construction 17 at one end and a delivery platform 19 at the other, said alleys being adjacent and each having lateral gutters 21 along their adjacent sides, and gutters 23 along their remotely situated sides, a ball return way 25 being provided between the adjacent gutters 21 of said alleys extending from the pits 17 to a ball rack 27 between the delivery platforms 19.

The runway or floor 15 of each alley is preferably carried in a supporting sub-structure comprising longitudinally extending members 29 disposed along the opposite sides of each alley 13. These members 29 are preferably formed in sections to facilitate and minimize the costs of transportation, and the sections are adapted to be assembled in end to end abutting relationship and secured together in any suitable or convenient fashion, as by bolting with fish plates, welding, or otherwise, as at 31 in Figure 3.

The sections also are provided with elongated openings 33 at intervals therein, there being two such openings at each end of each section whereby to form a set of four slot-like openings, preferably equally spaced at the abutting ends of the sections and each section also preferably pre-formed with a set of four elongated slots 33, preferably equally spaced apart in the medial portions of each section.

As shown in Figure 3 of the drawings, the longitudinally extending support members 29 may be carried at intervals on posts 35, which may suitably comprise preferably wooden piles or blocks upstanding from the floor or ground on which the alley is erected, and we provide mounting brackets 37 for supporting the members 29 adjustably on the posts 35.

These brackets 37 comprise plates 39 fastened on the posts 35 in any suitable or convenient manner, as by means of dowels 41, said plates carrying upstanding flanges 43 fastened on the plates 39, preferably by attaching angle irons 45 on the plate, as by welding or otherwise. On opposite sides of the posts 35 each plate threadingly receives an adjusting screw 47 extending adjacent the flange 43.

The support members 29 preferably comprise angle portions 47 and channel portions 49, which as shown in Figures 4 and 6, may comprise an integral unit with one flange of the angle portion 47 forming a flange of the channel portion 49, or, as indicated in Figure 5 of the drawings, the portions 47 and 49 may be formed as separate elements and suitably secured together to provide the support members 29, which consists of a flange 51 adapted to define the side edge of the floor structure, interconnected flange means 52 in position underlying the lateral edges of the floor structure, a web 53 depending from the flange means 52, said web 53 carrying the elongated slots 33 and being adapted to overlie the flange 43 on the base plate, the lower edge of said web 53 being formed with a flange 55 in position to extend above and seat upon the adjusting screws 47.

Opposite the openings 33 in the web 53 the support flange 43 is provided with an opening, and a nut 57 is preferably welded on said flange 43 at said opening in position to threadingly receive clamping screws 59 inserted through the openings 33 and threaded into the nut 57 whereby said screws 59 may be tightened or loosened.

in order to clamp the web 53 in adjusted position on the flange 43 merely by manipulating the heads of the fastening elements 59 from one side of the web 53, the nut 57 being anchored on the flange 43 and thus held stationary.

After the parts have been assembled with the fastening elements 59 loosely in place, the adjustment of the support members 29 to a desired elevation throughout the entire extent of the floor may be accomplished by adjusting the screws 47 and then tightening the members 59 in order to clamp the parts in adjusted position.

While the posts 35 may be arranged in any preferred, spaced-apart relationship and may be positioned opposite the junction 31 of the abutting ends of the members 29, I prefer to arrange the posts as shown in Figure 3 of the drawings, in which alternate posts are positioned at the abutting ends of adjacent members 29, the remaining posts being disposed at the mid-point in a member 29 since this arrangement permits the use of a minimum number of support posts 35 in providing adequate foundation support for the structure, and it is to permit this arrangement that the openings 33 are provided at the ends of each section 29 and also at the medial portions thereof.

We also provide at intervals in the support means 29 a plurality of gutter brackets 57 extending outwardly of and along the opposite edges of the structure 11; and we also provide, similarly spaced along and extending between the facing edges of the adjacent alleys 13, a plurality of alley connecting and gutter supporting brackets 59.

The brackets 57 are preferably of triangular form and preferably comprise a pair of pressed sheet metal plates which may be secured together in back-to-back relationship. These plates each comprise a web portion 61 and outstanding marginal flanges 63 at the edges of the plate.

The connecting brackets 59 likewise may comprise sheet metal plates of length between the opposite ends thereof sufficient to extend between the facing members 29 of adjacent alleys 13. Each bracket 59 comprises a plate portion 71 having marginal flanges 73 at the edges thereof, and the medial portions of the plates 71 are extended upwardly as at 75 to provide a mounting and support for the ball return way 25, the brackets 59 on opposite sides of said elevated portions 75 serving as support mountings adjacent alley gutters 21.

The plates in back-to-back relationship may be welded or otherwise suitably secured along their short edges on the web portion 53 of the support elements 29 in position extending substantially outwardly of the flange portion 51 of the support means 29.

The outwardly projecting portions of the brackets 57 serve to support the gutters 23 while the brackets 59 support the gutters 21 and the ball return means 25. The gutters 21 and 23 preferably comprise rolled sheet metal elements formed at one edge for connection with and along the marginal edges of said flange portion 51, said gutters to this end being formed with a dependent flange 65 forming a notch with the body of the gutter, in which notch the edge of the flange 51 may be received. The flanges 51 and 65 may be suitably secured together in any preferred fashion as by means of the fastening members 67.

The opposite edge of the gutter members 23 is provided with an upstanding flange 69 which, 75

if desired, may be curled in order to finish the raw edge of the gutter or may be provided with a finishing strip if desired.

We prefer, however, to utilize the edges 69 of the gutters 21 as a mounting for detachably receiving the opposed edges of the ball return trough 25, the same preferably comprising a rolled sheet metal strip, the opposite edges of which are curled, as at 77, to receive the flanges 69, the body of the strip extending between the spaced gutters 21 of adjacent alleys and forming a closure for said intermediate space.

In like fashion the edges 69 of the gutters 23 may carry a finishing strip 78, which, as shown in Figure 5, may serve to close the opening between the outer edge of a gutter 23 of one alley set 11 and the adjacent marginal edge of the gutter 23 of an adjacent alley set 11. The gutters 21 and 23 and the closure members 25 and 78 may be formed at intervals with drainage openings 82 in the bottoms thereof, this being a particularly desirable expedient where the alley is erected for outdoor use.

Intermediate the opposed edges defined by the flanges 65 and 69, the gutter elements have a generally circular sectional configuration, the radius of curvature being preferably slightly greater than the radius of a bowling ball; and the closure member 25 also may similarly have a generally curved sectional configuration if desired.

The gutter members 21 and 23 and the closure member 25 may be anchored as by means of the fastening members 81 on the upper flanged edges of the brackets 57 and 59, the fastening members 81 preferably comprising nuts and bolts with the heads of the bolts counter-sunk in the bottoms of the trough members 21, 23, and 25, the gutters 23 being anchored on the outstanding ends of the brackets 57 with the members 81 secured in the flanges 63 of said brackets, the gutters 21 being anchored on the opposed ends of the brackets 59 outwardly of the members 29, with the members 81 fastened in the flanges 73 and the closure member 25 being anchored upon the medial upstanding portions 75 of the brackets 59 with the fastening members 81 secured in the flanges 73 at the apex of the portion 75.

In order to facilitate the application of the fasteners 81 entirely from above the structure, the flanges 63 and 73 are perforated and nuts 84 adapted to threadably receive the screws 81, the same being welded on said flanges at said openings whereby application of the fasteners 81 may be accomplished merely by inserting the same through the corresponding openings in the members 21, 23, and 25, and threading the same into the stationarily mounted nuts 84 as by means of a screwdriver from above the trough members.

The gutters 21 and 23 and the ball return member 25 are preferably fabricated in convenient lengths for shipment, and are arranged in end-to-end abutting relationship, the abutting ends being secured together by clamps 83, the construction and arrangement of which is clearly illustrated in Figure 10 of the drawings.

Each trough section at one end is provided, preferably on each side of the depression 79, with a struck-out portion 83 forming an opening 85, the struck-out portion 83 being folded upon itself to form a shoulder 87 and perforated to receive a bolt 89. The struck-out portion 83 extends entirely upon the underside of the trough element, and the cut edge defining the end of the slot 85 opposite from the struck-out portion 83 is bent downwardly as at 91.

The struck-out portion 83 is also arranged so that the shoulder 87 extends at an angle facing upwardly toward the opening 85, the struck-out portions being perforated so that the bolt 89 may be inserted through the opening 85 and thence through the perforations of the struck-out portion. The adjacent end of the abutting channel member is provided with a flange member 91, which not only provides a rest for the edge of the channel member having the struck-out portion 83, thereby supporting said abutting edges in abutting relationship, but the member 91 also presents a threaded opening in position to receive the bolt 89, the threaded opening preferably being provided by welding a nut 93 on the flange member 91 at an opening therein so that by inserting the bolt 89 and tightening it into the nut 93, as by means of a socket wrench inserted through the opening 85, the parts may be clamped together by manipulations accomplished entirely from the upper side of the structure. At the same time, the fastening 81 is sealed entirely beneath the gutter members and the edge 91 is depressed so that bowling balls, in passing over the connection, are not in danger of becoming nicked upon the clamping means.

We prefer also to provide rails or tracks 95 on the gutters and on the return way 23. These rails, of course, may comprise grooves rolled integrally in the gutter members. We prefer, however, to form these tracks 95 as separate members prefabricated in standard lengths to facilitate shipment. The members 95 preferably are formed from sheet metal strips bent to provide a medial portion having a semi-circular sectional configuration providing a curved surface adapted to engage the balls and form tracks for carrying the same, the opposed edges of the strips being bent inwardly to form flanges defining a slot-like opening 101 therebetween to receive fasteners for securing the tracks on the bottoms of the gutters. Of course the track members 95 may be formed and fastened in place in any suitable fashion and not necessarily as illustrated and described herein, nor is our invention necessarily restricted to the fabrication of the track members as sheet metal elements.

In order to secure the track members on the gutters we preferably utilize snap-fastening means 97, the same preferably comprising lengths of springy wire having medial portions 99 bent as shown in Figures 7 and 8 to form a head adapted to be lockingly received in the openings 101 formed in the members 95, the opposed ends of the wire being bent to form opposed latching detents 103 having cam-like ends 105 adapted to snap into and lock in openings 107 formed at intervals in the gutter members. This locking action is accomplished merely by applying the track member 95 to the gutter member with the fasteners in position opposite the openings 107, and then pressing the parts together, the spring-like detents 103 being compressed together and thereby forced through the openings 107, and thereupon springing outwardly in position to perform the locking function.

In order to remove the rails 95 from mounted position it is merely necessary to compress the latches 103 in order to release the rail for removal, and this may be accomplished ordinarily by merely inserting a prying tool between the rail and the gutter on which it is mounted whereby to accomplish removal of the rails entirely from above the structure. We prefer, also, to form the bottoms of the trough members 21, 23,

5 and 25 each with a longitudinally extending trough-like depression 79 in which the rails 95 are mounted, as shown. The openings 107 for the fasteners 97 and the openings for the fastening members 81, and also, if desired, the clamp 83, may be arranged in said depressions whereby the rails 95 may insure that such balls as may travel in the troughs 21, 23, and 25 will not engage the fastening means 81 and 83.

10 The floors 15 of the alleys are carried on the spaced support means 29 between the flanges 51 thereof, the opposite edges of each floor resting upon the flange means 52. The floor 15 may, of course, be of any suitable or preferred construction. However, in order that the alley of our present invention may be weather-resistant, we prefer to form the floor 15 of weather-resisting material, and to this end the floor preferably comprises support means 111, shown in the illustrated embodiment as corrugated sheet material, said material being assembled on and between the flange means 52 with the corrugations extending laterally between the support means 29. The opposite edges of the corrugated sheet 111 15 are preferably anchored on the flange means 52 by fastening elements, such as nuts and bolts 109, arranged in the bottoms of the corrugations and secured in the flange means 52.

20 Upon the support means 111 we form a sub-layer floor 113, preferably comprising concrete, which, if desired, may be suitably reinforced by means of steel or other reinforcing members extending therein. Upon the layer 113 we apply a floor surfacing layer 115 of any suitable character, preferably a mastic, adapted to be finished to provide a hard, long-wearing, weather-resistant, upper surface. The floor layer 115 at its opposed edges may overlie upon the flange 65 25 of the gutter members 21 and 23 in order to provide a smooth joint between the parts.

30 The approach platforms 19 and the floor of the pits 17 may be formed in any suitable or convenient fashion. However, we prefer, in erecting the bowling alley, to make these floors of concrete, as shown at 121, the surface of the floor 35 forming the approach platforms 19 being level with and forming a continuation of the alley surface 15. If desired, the floor 19 may be extended as a single piece across the ends of all 40 of the alleys, and serve as a stop for the ends of the gutters 21 and 23 at the delivery end of the alleys, and the concrete as indicated at 123 45 may extend to form sloping shoulders at the ends of the gutters.

50 The pit floors preferably are formed as separate structures at the end of each alley, the floor level being somewhat below the level of the alley floors 15, the surfaces of the pit floors preferably coinciding with the level of the bottoms of the gutters 21 and 23. It will be noted that the 55 gutters preferably terminate at 125, short of the end of the alley floor 15 but within the wings of the pit structure, the terminal ends of the alleys being preferably beveled, as shown in Figure 14, and we provide gutter continuation pieces 127 extending between the ends 125 of the gutter and the end of the alley floor 15, as shown in Figure 14, said continuation pieces 127 being 60 preferably formed as rectangular troughs abutting the beveled ends 125 of the gutters, and closure pieces 129 are arranged at the inclination of the edges 125 to close the openings between the gutters 21 and 23, and the continuation pieces 127 at the abutting ends thereof.

65 70 The pit structures 17, as heretofore stated, may

be of any suitable style and construction. We prefer, however, to provide prefabricated metal elements including corner posts 131 which may be suitably anchored in the floor foundation or ground on which the alley is erected, as by driving the same into position. The posts 131 preferably comprise angle irons, the upper ends of which are interconnected by means of a rail 133, which also preferably comprises an angle iron, and the parts 131 and 133 may be interconnected as by bolting or welding, or by other suitable fastening means.

The rail 133 carries a back stop cushion 135, tiltably hung on the rail for swinging movement thereon between the posts 131. On each side of each alley we provide wings 137. The wings on the opposite sides of the alley set comprise posts 139 and 141, similar to the posts 131 and arranged in alinement with the posts 131 along the opposed sides of the alley set at the pit end thereof.

Metal plates 143 are provided for attachment on the sides of the posts 131, 139, and 141, facing inwardly upon the pit. A sheet of fibrous material 145 is applied as by means of rivets or other suitable fasteners 147 upon the pit facing surfaces of the sheets 143 in order to receive impact of balls striking the pit walls and to suppress the noise of impact. The posts 141 are preferably bent as shown, and form rails 149 which are secured to the upper ends of the posts 131 and 139. These rails 149 provide dependent flange means 151 to which the upper edges of the plates 143 may be secured, as by means of bolts 153. The rails 149 and the rail 133 have preferably sheet metal finishing members 155 mounted thereon, said members comprising preferably heavy gauge strips, the opposite edges of which are bent downwardly on opposite sides of the rails, as shown clearly in Figure 14.

Between the adjacent side walls 137 of adjacent alleys the pit wall structure comprises preferably a tubular post 157 substantially in line with the center of the ball return way 25. This post is of a size approximately equal to the width of the said return way and serves, with the members 131, as a support for sheet metal plates 163 similar to the plates 143 which extend on opposite sides of the post 157 to form the side walls of adjacent pits. These plates 163 preferably carry sound deadening fiber cushion sheets, similar to the members 145. The post 157 serves as a support for a gutter 165, an end of which is supported by and between the adjacent posts 131 of adjacent alleys, said end being curled upwardly as at 167. This gutter 165 extends substantially horizontally between the posts 131 and the post 157, and thereafter is inclined downwardly toward the end of the ball return way 25, the end of said gutter 165 opposite from its curled end 167 being arranged in abutting relationship and forming a continuation of the return way 25 at its pit end.

The gutter 165 has opposed curled edges adapted to receive and be secured on the upper edges of the plates 163, and the gutter 165, of course, may be provided with rails similar to and forming continuations of the rails 95 of the return way 25. The alley pit attendant, in order to return balls to the delivery end of the alley, merely places the same in the gutter 165 and allows the ball to enter the incline portion of the gutter. In descending said incline the ball receives sufficient impetus to travel the return way 25 to the delivery end of the alley.

At the delivery end of the alley a gutter 169

is provided between the delivery platforms 19 as a continuation of the return way 25. This gutter is preferably in sectional form similar to the return way and the gutter 165, and forms a continuation of the return way. To this end, the gutter 169 has a hump 171 adjacent the end thereof which abuts the end of the return way 25, said hump serving to decrease the rate of travel of balls entering the gutter 169 from the return way.

On the side of the hump 171 remote from the return way 25 we prefer to place a ball check 173 preferably comprising a sheet metal strap 173 arranged in Figure 12 of the drawings, said strap being fastened on the under side of the gutter 169 and forming a loop thereover through which returning balls are required to pass. In the upper portions of the loop we provide a spring pressed plate 175 pivoted on the strap 173, as at 178, the plate 175 being normally pressed as by means of a spring 179 into position within the strap to engage a ball in passing through the strap and thereby check the movement thereof. In order to protect the returning balls from scuffing upon contact with the check plate 175, the same may be surfaced with any suitable material, such as a fiber pad 181.

The end of the gutter 169 remote from the return way 25 is supported on a post 183 preferably comprising corrugated sheet metal, one end of which is anchored in the ground between the platforms 19 and the upper end of which is finished preferably by means of a sheet metal cap 185.

The gutter 169 may be supported at intervals in any suitable fashion, as by means of posts 187 sunk in the ground between the platforms 19 and carrying plates 189 attached thereto, to which plates the gutter may be secured as by fastening means similar to the fasteners used in securing the gutter 21 and the return way 25 upon the bracket 71.

It will be seen from the foregoing that we have provided an unusually simple and inexpensive construction made of parts adapted for prefabrication and erection at any desired site merely by bolting or otherwise securing the parts together. The construction is entirely weather-proof and can be erected out of doors without the provision of any enclosing structure, if desired. The assembly further is facilitated by the provision of fastenings 81, 83, and 97, which may be accomplished entirely from above the structure. The tracks 95 may be removed and replaced easily; likewise, the return way pieces 25 may be readily removed at any point in the alley in order to afford access to the adjusting and clamping screws 47 and 59. All of the elements of the construction, except the flooring, may be made in sizes to permit of transportation at minimum cost. Furthermore, the construction may be disassembled and moved from place to place, if desired, at a fraction of the expense required to tear down and move bowling alleys of usual construction; in fact, it is virtually impossible to move alleys of ordinary construction due to the exorbitant expense and breakage which is encountered and which makes it cheaper to buy and install a new alley rather than to attempt moving an old one. It is thought that the invention and its numerous attendant advantages will be fully understood from the foregoing description, and it is obvious that numerous changes may be made in the form, construction, and arrangement of the several parts without depart-

ing from the spirit and scope of the invention, nor sacrificing its attendant advantages, the form herein disclosed being merely for the purpose of demonstrating the invention.

The invention is hereby claimed as follows:

1. A bowling alley comprising monolithic means forming an alley floor structure, sheet metal trough means forming gutter sections supported in end to end abutting relationship along an edge of said floor structure, and means to removably connect the abutting ends of said sections comprising means forming a dependent flange on one section and carrying threaded means for receiving a bolt, means forming a dependent bolt-receiving lug on the abutting section adjacent an opening therein, and a bolt adapted to be inserted through said opening and into said receiving lug in position to threadingly engage the threaded means on said flange in order to clamp the parts together.

2. A bowling alley comprising rail means providing a ledge, monolithic hardened plastic slab means forming an alley floor having a longitudinal edge defined by said rail means, said slab means having an edge supported on said ledge, and sheet metal trough means forming an edge gutter along and outwardly of the longitudinal edge of said floor, said trough means having an edge flange interfitting with said rail means and held in place by said monolithic means along an edge of said floor.

3. A bowling alley comprising rail means forming a ledge and an upstanding rib, monolithic slab means forming an alley floor having a longitudinal edge defined by said rib and supported on said ledge, and sheet metal trough means forming an edge gutter for said floor, said trough means having an edge flanged and hooked upon said rib and held in place thereon by said slab means.

4. A bowling alley comprising rail means providing a ledge, monolithic hardened plastic slab means forming an alley floor having a longitudinal edge defined by said rail means, said slab means having an edge supported on said ledge, and sheet metal trough means forming an edge gutter along and outwardly of the longitudinal edge of said floor, said trough means having an edge flange interfitting with said rail means and held in place by said monolithic means along an edge of said floor, said rail means including mounting means extending beneath said ledge and a bracket secured on said mounting means beneath said ledge and extending outwardly thereof in position to support the edge gutter outwardly of the longitudinal edge of said floor.

5. A bowling alley comprising rail means providing a ledge, monolithic hardened plastic slab means forming an alley floor having a longitudinal edge defined by said rail means, said slab

means having an edge supported on said ledge, sheet metal trough means forming an edge gutter along and outwardly of the longitudinal edge of said floor, said trough means having an edge flange interfitting with said rail means and held in place by said monolithic means along an edge of said floor, and a bracket secured on said rail means beneath said ledge and extending outwardly thereof in position to support the edge gutter outwardly of the longitudinal edge of said floor.

6. A bowling alley comprising means forming an alley floor, channelled members in end-to-end relationship forming longitudinally extending floor supporting rail means defining the opposed edges of said floor, longitudinally extending sheet metal means forming a gutter secured at its edge along a longitudinal edge of said floor, sheet metal trough means forming a return trackway for balls, said trough means having an edge secured to the floor remote edge of said gutter, and sheet metal means forming bracket plates supporting said gutter and return trackway at intervals on said longitudinally extending floor supporting rail means.

7. A bowling alley comprising means forming a pair of adjacently extending alley floors, each floor being supported on longitudinally extending floor supporting members at the edges thereof, sheet metal edge gutters extending at and having edges secured along the adjacent edges of adjacent floors, means connecting the adjacent edges of said gutters, and gutter supporting brackets connected between the longitudinally extending support members of adjacent floors.

8. A bowling alley comprising monolithic means forming an alley floor, and sheet metal trough means forming a gutter having an edge embedded in said monolithic means along a longitudinal edge of said floor.

9. A bowling alley comprising means forming a pair of adjacently extending alley floors, longitudinally extending floor supporting rail means at the adjacent edges of said floors, sheet metal trough means forming a gutter bordering each of the adjacent edges of said floors, each gutter having an edge secured along a longitudinal edge of the floor which it borders, elongated sheet metal cover means having opposed edges secured to the floor remote edges of said gutters to interconnect the same and close the space therebetween, and spaced plates forming brackets for supporting said gutters at intervals, each bracket being secured to and extending between said longitudinally extending floor supporting members and affording common support for both gutters and said cover.
